COMPUTER

Nathan W. Feldman, Newark, N. J.

Application September 19, 1945, Serial No. 617,415

3 Claims. (Cl. 235—78)

(Granted under the act of March 3, 1883, as
amended April 30, 1928; 370 O. G. 757)

1

This invention relates to computers and particularly to a disc computer for use in determining the ampere hour discharge of storage batteries during testing operations.

In testing conventional storage batteries it is customary after charging a battery to discharge the same at a constant rate, for example, at the rate of about 10 amperes per hour. A record is made of the starting time of the test, and discharge is continued until voltage of the storage battery drops below a predetermined minimum, at which time the test is automatically terminated and a record of the finish time made.

Computation of the ampere hour discharge of the battery involves figuring the lapse of time between the start of the test and the finish thereof, and multiplying such lapse of time by the rate of discharge, for example, 10 amperes per hour. The present invention provides a disc computer in which only a single setting need be made to perform the computation. This setting consists in adjusting the discs of the computer to indicate the starting time of the test and it is then possible to read the finishing time on the computer and in registration therewith will be found the final answer expressed in ampere hours.

In certain storage batteries discharge is at the rate of 10 amperes per hour for a period of ten hours. The rated discharge capacity is therefore one hundred ampere hours. In such cases the finally computed discharge for any particular battery expressed in ampere hours is also an expression of the percent of rated discharge capacity. Thus for example a battery having a discharge of 90 ampere hours also has ninety percent of the rated discharge capacity. Therefore the final answer of the disc computer may be considered either as being ampere hours of discharge or percentage of the rated discharge capacity.

An object of the invention is to provide a disc computer for use in determining the ampere hour discharge of storage batteries during test operations.

Another object of the invention is to provide a disc computer in which a single setting only is necessary to compute the ampere hour discharge of a storage battery during test operations.

A further object is to provide a disc computer which may be adjusted to indicate the starting time of the test and on which the finishing time may be read, and in registration with the finishing time the final answer in ampere hour discharge.

A further object is to provide a disc computer

2

in which the final answer may be expressed in percent of rated discharge capacity.

Further objects and advantages of this invention, as well as its construction, arrangement and operation, will be apparent from the following description and claims in connection with the accompanying drawings, in which,

Figure 1 is a top plan view of a preferred form of the invention.

Figure 2 is an exploded view of the discs forming part of the computer shown in Figure 1.

Figure 3 is a fragmentary view in enlarged section taken substantially along line 3—3 of Figure 1.

With reference to the drawings in detail, the computer forming the present invention comprises an ampere hour disc 11, a minute disc 12, an hour disc 13 and a masking disc 14. Ampere hour disc 11 is of largest diameter, minute disc 12 is of next largest diameter, masking disc 14 is the next largest diameter and hour disc 13 is of smallest diameter. These four discs are arranged concentrically with ampere hour disc 11 on the bottom and with discs 12, 13 and 14 arranged thereabove in that order. Discs 11, 12, 13 and 14 are mounted upon a spindle 15 (Figure 3) having an enlarged head 16 below ampere hour disc 11. A washer 17 is disposed on spindle 15 above disc 14, and a locking nut 18 secures the discs in place upon spindle 15.

Discs 12, 13 and 14 are locked together by a cotter pin 19 having an enlarged head 20 above disc 14, and having legs 21 which are spread apart beneath disc 12. An arcuate slot 22a is formed in disc 13 and cotter pin 19 extends through slot 22a whereby disc 13 may be rotated through an arc relative to discs 12 and 14.

Disc 14 is provided with an observation opening 22 and is further provided with a series of four openings 23, 24, 25 and 26, spaced 90° apart from each other about the periphery of the disc. Disc 14 is further provided with an arcuate cut away portion 27 whereby disc 13 is accessible for manual rotation thereof relative to discs 12 and 14.

By way of illustration but not limitation, the present disc computer is shown as designed for use in connection with tests performed on storage batteries arranged to discharge at the rate of 10 amperes per hour. To this end ampere hour disc 11 is graduated from a value of 90.0 progressively in a clockwise direction to a value of 120.0 through an arc of 270 degrees. Thus the value of the graduations increase by 10.0 for each 90° of clockwise progression on disc 11. For convenience the graduations have been extended coun-

terclockwise beyond the 90.0 mark to a terminal mark of 87.0 and likewise have been extended beyond the 120.0 mark in a clockwise direction to a terminal mark of 123.0.

Minute disc 12 is graduated through 270 degrees so that each 90° corresponds to an interval of one hour which is divided into 60 minutes. For convenience the graduations are extended slightly beyond the 270 degree range.

Disc 13 is provided with a series of numerals from one to twelve which may be viewed through observation opening 22 in disc 14. Rotation of disc 13 may be effected to bring any one of the numerals desired into view through opening 22. A similar series of numerals is provided beneath each of openings 23, 24, 25 and 26, and these are so arranged that the time interval between the numeral exposed to view through opening 22 and the numeral exposed through openings 23, 24, 25 and 26 will be respectively 9 hours, 10 hours, 11 hours and 12 hours. For example as shown in Figure 1, if disc 13 is adjusted so that the numeral 10 is seen through opening 22, then the numeral 7 corresponding to an interval of 9 hours will be seen through opening 23.

To illustrate operation of the computer assume, for example, that it is desired to compute the ampere hour discharge of a battery from which the following test data has been recorded:

Starting time----- 10:00 a. m.
Finish time----- 7:30 p. m.
Discharge rate----- 10 amperes per hour

Discs 12, 13 and 14 are rotated as a unit until opening 23 of disc 14 and the corresponding zero minute mark of disc 12 are in registration with the 90.0 ampere hour mark of disc 11. Disc 13 is then manually rotated relative to discs 12 and 14 until the numeral corresponding to the starting hour of the test run upon the battery may be seen through opening 22. In the example if the test were started at ten o'clock a. m., adjustment would be made until the numeral 10 showed through the opening 22 as seen in Figure 1. Discs 12, 13 and 14 are then rotated as a unit relative to disc 11 until the number of minutes past the hour corresponding to the exact starting time of the test are in registration with the 90 ampere hour mark. In the example, since the starting time is exactly ten o'clock a. m. no adjustment of this nature will be made and the zero minute mark of disc 12 will be in registration with the 90.0 ampere hour mark of disc 11.

The finish time in hours and minutes is then located on the computer, selecting the proper hour at opening 23, 24, 25 or 26 and then locating the correct minute position clockwise therebeyond on disc 12 as the answer index. In the example, with a finishing time of 7:30 p. m., the number 7 is seen through opening 23 and the thirty minute mark clockwise therefrom is found to be the answer index. When the finishing time is correctly located on disc 12 as the answer index, the graduation on disc 11 in registration therewith will indicate the answer in ampere hour discharge of the battery. In the example, the answer on disc 11 will be found to be 95.0 ampere hours.

It will be apparent that the computer is designed for use in connection with batteries which discharge at the rate of ten amperes per hour since the ampere hour graduations on disc 11 vary by 10 ampere hours for each hour of variation on minute disc 12.

It will also be apparent that the computer is

designed for use with batteries which are arranged to discharge to the predetermined voltage minimum over a period of from 9 to 12 hours since minute disc 12 and hour disc 13 are designed to cover such a time interval.

It is to be understood that the graduations on the ampere hour disc, the minute disc and the hour disc may be modified in suitable manner to accommodate the computer for use with storage batteries having rates of discharge and length of discharge time which differ from the specific illustrations herein.

It is to be understood that various modifications and changes may be made in this invention 15 without departing from the spirit and scope thereof as set forth in the appended claims.

The invention described herein may be manufactured and used by or for the Government of the United States of America for governmental 20 purposes without the payment of any royalties thereon or therefor.

What is claimed is:

1. A computer comprising a pivot, an answer disc on said pivot having function graduations 25 thereon representing a function which varies with time, a minute disc on said pivot concentric with said answer disc and rotatable relative thereto and having minute graduations thereon in registration with said function graduations, a masking disc on said pivot for rotation with said minute disc and having peripheral openings in registration with said minute graduations at 60 minute intervals and also having a random opening, an hour disc on said pivot between and rotatable relative to said masking disc and said minute disc and inscribed with a series of numerals beneath said masking disc openings whereby when a numeral is exposed beneath said random opening the numerals beneath successive 40 peripheral openings will differ from said random opening numeral so as to successively indicate an increasing time lapse in hours, an arcuate slot in said hour disc, and means extending through said slot for locking said masking disc and minute disc together and for limiting rotation of said hour disc relative to said masking disc and said minute disc.

2. A computer for use in determining the ampere hour discharge of a storage battery comprising 50 a pivot, an ampere hour disc on said pivot having ampere hour graduations thereon, a minute disc on said pivot concentric with said ampere hour disc and rotatable relative thereto and having minute graduations thereon in registration with said ampere hour graduations, a masking disc on said pivot for rotation with said minute disc and having peripheral openings in registration with said minute graduations at 60 minute intervals and also having a random opening, an hour disc on said pivot between and rotatable relative to said masking disc and said minute disc and inscribed with a series of numerals beneath said masking disc openings whereby 55 when a numeral is exposed beneath said random opening the numerals exposed beneath successive peripheral openings will differ from said random opening numeral so as to successively indicate an increasing time lapse in hours, an arcuate slot in said hour disc, and means extending through said slot for locking said masking disc and minute disc together and for limiting rotation of said hour disc relative to said masking disc and said minute disc.

3. A computer for use in determining the ampere hour discharge of a storage battery which

discharges at the rate of ten amperes per hour comprising a pivot, an ampere hour disc on said pivot having ampere hour graduations thereon from 90.0 to 120.0 through an arc of 270°, a minute disc on said pivot concentric with said ampere hour disc and rotatable relative thereto and having minute graduations through 270° with each 90° graduated from 0 to 60, said minute graduations being in registration with said ampere hour graduations, a masking disc on said pivot for rotation with said minute disc and having peripheral openings at 90° intervals in registration with said zero minute graduations and a random opening, an hour disc on said pivot between and rotatable relative to said masking

10
15

disc and said minute disc and inscribed with a series of numerals from 1 to 12 beneath said masking disc openings whereby when a numeral is exposed beneath said random opening the numerals exposed beneath successive peripheral openings will differ from said random opening numeral so as to successively indicate a time lapse of 9 to 12 hours, an arcuate slot in said hour disc, and means extending through said slot for locking said masking disc and minute disc together and for limiting rotation of said hour disc relative to said masking disc on said minute disc.
